[57] **CLAIM**

The ornamental design for a combined supported re-

DESCRIPTION

FIG. 1 is a view in perspective of a combined supported reflector and arm-supported suspended beam useful for solar buildings and the like according to my invention, and representing a view of what may form the front-/side, or rear/side, or vice versa, of such combined supported reflector and arm-supported suspended beam for solar buildings and the like, but which for ease of description will be designated as a front/side view.

FIG. 2 is a rear view in perspective, taken in the opposite direction from FIG. 1.

FIG. 3 is a front elevation view of the combined supported reflector and arm-supported suspended beam useful for solar buildings and the like of FIG. 1, according to the illustrative convention adopted for FIG. 1.

FIG. 4 is a plan view of the combined supported reflector and arm-supported suspended beam useful for solar buildings and the like of FIG. 1.

FIG. 5 is a rear elevation view of the combined supported reflector and arm-supported suspended beam useful for solar buildings and the like of FIG. 1.

FIG. 6 is a side elevation view of the combined supported reflector and arm-supported suspended beam useful for solar buildings and the like of FIG. 1.
